UNITED STATES PATENT OFFICE.

NELLIE S. DAY, OF SPRINGFIELD, MASSACHUSETTS.

DESIGN FOR AN EFFIGY.

50,650.

Specification for Design.

Patented Apr. 24, 1917.

Application filed February 9, 1917. Serial No. 147,719. Term of patent 7 years.

To all whom it may concern:

Be it known that I, NELLIE S. DAY, a citizen of the United States, residing at Springfield, in the county of Hampden and State of Massachusetts, have invented a new, original, and ornamental Design for an Effigy, of which the following is a specification, reference being had to the accompanying drawings, forming part thereof.

In the drawings:

Figure 1 is a front view, and

Fig. 2 is a side view of an effigy showing my new design.

I claim:

The ornamental design for an effigy as shown.

N. S. DAY.
